NELSON K. SMITH, OF LOS ANGELES, CALIFORNIA, ASSIGNOR, BY MESNE ASSIGNMENTS, TO THE GUIBERSON CORPORATION, OF DALLAS, TEXAS, A CORPORATION OF DELAWARE.

WELL APPARATUS.

Application filed November 8, 1926. Serial No. 146,975.

This invention relates to well apparatus, and more particularly to catchers for well tubing, which catchers operate to prevent drop of tubing strings in the well in case of 5 failure in the support of tubings or the severance of the strings.

The present invention, in accordance with standard practice provides for automatic action of the tubing catcher after commencement of introduction of the string of tubing within the well casing. The present catcher is so organized that it will operate automatically while the string of tubing is being lowered in the well, while it is in position in the 15 well, and while it is being withdrawn from the well. In inadvertent or accidental drop of the tubing, or severance thereof at a point above the tubing catcher, will cause the automatic action of the catcher for its engagement with the well casing so as to check descent of the tubing after a momentary drop, and thus prevent damage or destruction to the string of tubing or the well itself.

In accordance with the present invention, 25 means are provided whereby the catcher may be voluntarily operated to cause the string of tubing to be locked within the well casing, and the string of tubing may be readily withdrawn from the casing after such voluntary 30 locking operation.

The invention has for its objects the provision of an improved catcher or well apparatus of the general character stated which will be superior in point of relative simplicity and 35 inexpensiveness of construction, taken in conjunction with durability, reliability, length of life, positiveness in action and general serviceability, and which will be generally superior in point of efficiency.

40 With the above and other objects in view, the invention consists in the novel and useful provision, formation, combination, association and relative arrangement of parts, members and features, all as hereinafter described, shown in the drawings, and finally pointed out in claims.

In the drawings:

Figure 1 is a fragmentary elevation of a 50 string of tubing incorporated in which is applied to which is a catcher constructed and organized to embody the present invention, the same being shown surrounded by a section of well casing;

Figure 2 is a fragmentary elevation similar

to that in Figure 1, with the parts slightly 55 axially rotated, parts being shown broken away for clearness of illustration;

Figure 3 is a vertical sectional view, partly in elevation, taken upon the line 3—3, Figure 2;

Figure 4 is a view upon a reduced scale similar to Fig. 3, further parts being shown in elevation;

Figure 5 is a section, partly in elevation, similar to Fig. 3, the tubing catcher being shown with the parts in positions consequent upon manual or voluntary locking of the catcher to lock the tubing against descent in the well casing, the parts shown in Figs. 1, 2, 3 and 4 being shown with the catcher parts 65 unlocked, or so that the string can descend;

Figure 6 is a view similar to Fig. 4, showing, however, the parts of the catcher in positions consequent upon the initiated drop of the tubing, which has caused the automatic action of the catcher to prevent further drop;

Figure 7 is an enlarged detail sectional view, with parts further in section, showing certain of the features shown in Fig. 6;

Figure 8 is a bottom end view of one of the sliding collars, separated by the coil spring shown in the other figures, the same being upon the scale of Fig. 5;

Figure 9 is a fragmentary vertical sectional view of certain features of the catcher shown in the other figures and including the lower sliding collar and a portion of the coil spring bearing downwardly thereupon, together with a portion of the rein of one of the catcher slips, the said lower sliding collar being in its lowermost position;

Figure 10 is a similar view, with further features, showing the said lower sliding collar in elevated position;

Figure 11 is a detail transverse sectional view taken upon the line 11—11 Fig. 3, and looking in the direction of the appended arrows;

Figure 12 is a detail transverse sectional view, taken upon the line 12—12, Fig. 3, and looking in the direction of the appended arrows;

Figure 13 is an enlarged detail transverse sectional view, taken upon the line 13—13, Fig. 2, looking as directed by the arrows; and,

Figure 14 is a detail transverse sectional

view, upon an enlarged scale, taken upon the line 14—14, Fig. 1, and looking in the direction of the appended arrows.

Corresponding parts in all the figures are 5 designated by the same reference characters.

Referring with particularity to the drawings, I have shown at A and B, respectively, two joints of well-tubing, with which are associated the features, parts and members of

- 10 the improved tubing catcher, which includes a fixed collar 15 threaded on to the upper end of the joint A and lower end of the joint B, and upon which are formed ways 16, which are upwardly and outwardly inclined, and
- 15 with which co-act slips or dogs 17 adapted to co-act with such collar 15 and the string of tubing on the one hand, and the well casing 18 on the other hand, in order to lock the tubing and well casing together and prevent de-
- 20 scent thereof. C designates generally means for voluntarily or manually causing such locked relation, in order to lock the string of tubing in the well casing at any point and at any time desired; and D designates means
- 25 for automatically actuating the tubing catcher to cause such locked inter-relation between the tubing and the casing. Such means D are constructed and organized to operate upon an inadvertent or accidental drop or
- 30 lowering of the string of tubing resulting from failure of the elevator or other means suspending the string of tubing at the mouth of the well, or upon a breaking of the string of tubing, as by the failure of the collar connecting adjacent joints thereof, or otherwise.
- 35 The slips 17 are adapted to move vertically in the ways 16, and outwardly when raised and inwardly when lowered, and to such ends are respectively directly actuated by feet 17^a
- 40 depending from the slips, and reins 17^b rising from the slips. The feet 17^a, following the general teachings of an earlier application for Letters Patent filed by me January 18, 1926, Serial No. 82,085, for tubing catchers,
- 45 normally depend within vertical slots 19 or spaces between prongs 20 rising from a collar 21 loosely surrounding the tubing joint A, and joined with a similar loose collar 22 by outwardly bowed friction springs 23 having
- 50 flattened faces frictionally engaging with the inner surface of the well casing 18. These prongs 20 rise within a centering collar 24 surrounding the tubing joint A and rigidly suspended from the coupling 15, such center-
- 55 ing collar having a slotted or interrupted annular bead or rib 24^a slightly spaced from the inner wall of the well casing 18, and co-acting with a further spacing collar 25 threaded upon the tubing joint B above the other features of the tubing catcher, to center the tubing and the catcher within the well casing, so as to properly present to the casing the features which co-act therewith in a proper balanced relation. The centering collar 25
- 65 is likewise provided with a vertically slotted

bead or rib 25^a which directly co-acts with the well casing in coordination with the bead or rib 24^a of the centering collar 24. The vertical slotting or notching of the beads or ribs permits the lowering of the tubing and 70 tubing catcher through fluid in the well casing. A collar or coupling 26 upon the tubing joint A, or between it and the next lower tubing joint, serves to limit downward movement of the sliding collar 22. When it is desired to manually or voluntarily actuate the slips 17 upwardly and outwardly to set the string of tubing in the well casing and lock it in position against further descent, it is only necessary to pull the string of tubing 80 upwardly, raising the feet 17^a which depend from the slips, rotating the tubing slightly clockwise, looking downwardly, whereupon the feet 17^a will be brought to rest upon the prongs 20; and when the string is again permitted to exert its downward thrust the bowed springs 23 will hold collar 21 and the prongs 20 relatively stationary, whereupon the ways 16 will be lowered and the slips 17 thrust upwardly and outwardly into positions such as shown in Figure 5, wherein they are wedged effectively between the ways and the well casing and, due to their transversely serrated outer surfaces, as shown at 17^c they are caused to bite into the casing, with their 90 downwardly and outwardly-presented serration edges, effectively locking the tubing to the casing to prevent further descent of the former. In order to unlock the tubing from the casing it is only necessary to pull up upon the string, whereupon the ways 16 travel upwardly along the inner faces of the slips, and the slips become released from their locked positions. If it is then desired to lower the string further, the tubing when 100 elevated slightly, is turned counter-clockwise looking downwardly to bring the feet in registration with the slots 19, whereupon the string may then be lowered and the feet will enter the slots 19, and the prongs bearing up against the lower end portion of the collar 15 will be forced downwardly, also forcing downwardly the sliding collars 21 and 22 with the bowed springs connecting the same, and overcoming the friction between said springs and the well casing. 110

The rein 17^b of the slips 17 rise through slots 16^a the tops of the ways 16, and at their upper ends are bent into hooks 17^d which enter radial openings 27 in the lower end portions of spaced fingers 28 in the slip actuator E, which loosely and slidably surrounds the tubing joint B to accommodate within the same other parts to be specified. These fingers 28 loosely interlock with upwardly rising fingers 29 upon the collar 15, maintaining such collar 15 and slip actuator in rotative couple, so that at all times the slip actuator is in position to actuate the slips 17, in vertical direction. The hooks 17^d are inwardly di- 120

rected so that their outer end portions are directed outwardly through the openings 27. Slidably mounted upon the tubing joint B within the slip actuator E are upper and lower adjustable tension collars 30 and 31, which may each be reversed end for end, the collar 30 having, as shown positioned in the drawings, and particularly Fig. 3, an upper portion 30^a of lesser outside diameter and a lower portion 30^b of greater outside diameter; and the lower adjustable tension collar 31, as positioned in Figure 3, having an upper portion 31^a of relatively greater outside diameter and a lower portion 31^b of relatively smaller outside diameter. These upper and lower portions in each instance only extend part way about the collars, as clearly shown in Figs. 4 and 8. These limited portions of the collars are slidably mounted in slots 32 formed in the slip actuator E, through which slots also play outwardly bowed elongated friction springs 33, having at their lower ends hooks 33^a taking into the openings 27 and having at their upper ends hooks 33^b resting upon the upper end of the upper adjustable tension collar 30. These springs 33 bear frictionally against the inner wall of the well casing 18. These springs partially sustain the weight of the slip actuator E. Between the tension collars 30 and 31 a coil compression spring 34 surrounds the tubing joint B bearing upwardly upon the tension collar 30 and downwardly upon the tension collar 31; and in accordance with the adjustment of said collars and the end of which is uppermost in each instance, exerting a tendency to a greater or lesser extent to cause frictional engagement of said bowed springs with the inner surface of the well casing.

The collar 25 serves to limit the upward play of the slip actuator E and prevents displacement of the slips 17 from the ways 16.

Taking up now the mode of operation of the device as an entirety, it will be understood that the string of tubing with the catcher elements and features are introduced within the well casing 18 with the feet 17^a on the slips accommodated in the spaces 19 between the prongs 20. The slips are therefore in the lowered positions as shown in Figures 1 to 4 inclusive of the drawings. This condition is maintained by the slip actuator E the gravitational effect of which is slightly greater than the frictional retardation of the bowed springs 33. It is to be stated in this connection that the downward and inward positioning of these slips under the predominating weight of the slip actuator E is assisted by downwardly and inwardly inclined bores 15^a in keepers 15^b provided at the lower end of the coupling or union 15. The keepers 15^b are beveled off at their top surfaces, as at 15^d, and the slips 17 are similarly chamfered or beveled as at 17^d to fit and co-act with said beveled portions 15^d of the keepers to prima-

rily support the weight of the slips and the slip actuator E when they are in normal lowered condition as shown in Figures 1 to 4 inclusive. The feet 17^a pass through these bores. The coil spring 34 is in its maximum compression during the introduction of the tubing and attendant features in a well casing, and during the lowering of the same within the casing to the desired level in the hole. The exertion of this compression of the spring 34 causes maximum spacing apart of the collars 30 and 31 and causes one or more of the enlargements of the two adjustable tension collars 31 and 30 to bear against the bowed springs 33 adjacent either the bottom or the top of each thereof or against both bottom and top, in accordance with the adjustment of such collars, and their position upon the tubing. This causes the operative minimum friction of the bowed springs within the well casing for any given period of introduction and lowering of the tubing in the casing. The action of the adjusting collars 30 and 31, under this maximum compression of the coil spring 34, is to cause a flattening of the bowed formations of the springs 33, so as to produce the said minimum friction of said springs upon the well casing. If, now, the tubing is dropped in entirety, as by failure of support at the mouth of the well, or a fracture or severing of the tubing takes place above the tubing catcher elements, the spring 34, hitherto under its maximum compression, tends to expand. This is permitted by the falling of the tubing with its collar 15 within which is formed a seat 15^c against which the lower portion of the collar 31 has rested during the lowering of the tubing and catcher. In other words, the shoulder 15^c falls away from the collar 31, permitting the forcing down of said collar 31 by the spring 34. As the spring 34 relaxes in its compression the upward pressure of the collar 30 against the upper ends of the bowed springs 33 is relaxed, permitting such springs to assume a more pronouncedly bowed formation, thus increasing the friction thereof within the well casing. Thus, the maximum friction of the bowed springs for any given use and operation of the device is set up, and this maximum friction arrests the slip actuator E in its fall in company with the string and other features, setting up a differential between such rate of fall and the rate of fall of the tubing. The result of this differential component is to likewise arrest the slips 17 in their participation in the common fall of parts and elements, so that a differential is set up between the rate of fall of the slips and the rate of fall of the tubing with its collar 15 and the slip-ways 16 thereon, and the slip-ways wedge the slips outwardly into the positions shown in Figures 6 and 10, wherein they arrest further fall of the tubing and associated parts. When it is desired now to

withdraw the tubing from within the casing it is only necessary to pull upwardly on the string, whereupon the tubing becomes freed from the casing by the release of the slips, the ways riding upwardly within the group of slips, and the slips thus retreating from the casing in relative downward and inward motion. All of the parts which have to do with the automatic action described, including the 10 spring 34 and bowed springs 33 and collars 30 and 31, then assume their normal conditions and positions and the string may be again supported or suspended within the casing for further automatic action, unless it is necessary to perform a fishing job and remove the whole string. The slip actuator E has a lip e overlapping the collar 30.

It will be obvious, due to the well-established mechanical equivalence of a spring and a weight, that the catcher device may be modified, aside from other considerations, by eliminating the upper adjustable tension collar 30, together with the coil spring 34, and utilizing merely the adjustable tension collar 31 or the equivalent, as primarily a weight, to act upon the friction of the springs or bowed springs 33 upon the drop of the tubing string and the lowering of such collar 31 or its equivalent permitted by the resultant drop of the collar or union 15. In this case, the upper end of the springs 33 could be riveted to the slip actuator member E, at the upper portion thereof. This is such an obvious modification, within the doctrine of mechanical equivalence, that it is not deemed necessary to separately illustrate it in the drawings.

At no time in the operation of this device are the slips or dogs poised upon or sustained in a poised relation by the coil spring 34, and if desired the bowing of the springs 33 may be so adjusted and the parts so inter-related with such bowed springs that the coil spring 34 may be eliminated.

I have already described the voluntary operation of the device in order to lock the tubing in the well casing by means of the slips 17 and the collars 21 and 22 and their bowed springs 23. It will be understood that this operation is an independent operation performed whenever desired to voluntarily establish the locked relations mentioned. Of course, the automatic features may be utilized independently of the voluntary features, although they are effectively used together.

It will be obvious that many changes, variations and modifications may be made in practicing the invention, in departure from the specific provision and construction and interrelation of parts, members and features heretofore described and disclosed in the drawing, without departing from the true spirit of the invention.

Having thus disclosed my invention, I claim and desire to secure by Letters Patent:

1. In combination with a string of tubing

or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like.

2. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means for increasing the frictional action thereof upon a sudden lowering of the string or the like; said friction means comprising a bowed spring.

3. In combination with a string of tubing or other structure adapted to be lowered in a well casing; slips, means upon the string or other structure adapted to cooperate with the slip to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; there being a slip-actuator movably mounted in connection with said string or the like and with which said slips or the like are connected.

4. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; there being a slip-actuator movably mounted in connection with said string or the like and with which said slips are connected; said friction means being mounted in connection with said slip actuator.

5. In combination with a string of tubing or other structure adapted to be lowered in a well casing; slips, means upon the string or other structure adapted to cooperate with the slips to cause the same to wedge against the well casing; means co-acting with the slips and frictionally co-acting with the

- casing to permit the string or the like to be lowered with the slips in retracted position, and means cooperating with said last named means for increasing the frictional action thereof upon a sudden lowering of the string or the like; there being a slip actuator movably mounted in connection with said string or the like and with which said slips are connected; said friction means being mounted in connection with said slip actuator; the weight of said slips and slip actuator minus the moment of said frictional means being normally carried by the string or the like.
6. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby.
7. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby; further means being provided urging said last named member toward its normally supported position.
8. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby; further means being provided urging said last named member toward its normally supported position; and a further member mov-
- ably mounted in connection with the tubing or the like and between which and said first named movable member said last named means is disposed.
9. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby; further means being provided urging said last named member toward its normally supported position; and a further member movably mounted in connection with the tubing or the like and between which and said first named movable member said last named means is disposed; said last named means comprising a coil compression spring.
10. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby; further means being provided urging said last named member toward its normally supported position; and a further member movably mounted in connection with the tubing or the like and between which and said first named movable member said last named means is disposed; said last named means comprising a coil compression spring.
11. In combination with a string of tubing or other structure adapted to be lowered in a well casing; slips, means upon the string or other structure adapted to cooperate with the slips to cause the same to wedge against the well casing; means co-acting with the slips and frictionally co-acting with the casing to permit the string or the like to be lowered with the slips in retracted position, and means cooperating with said last named means for increasing the frictional action thereof upon a sudden lowering of the string or the like; said last named means including a movable member mounted in connection with said tubing and normally supported thereby; further means being provided urging said last named member toward its normally supported position; and a further member mov-

a sudden lowering of the string or the like; said last named means including a movable member mounted in connection with said tubing and normally supported thereby; further means being provided urging said last named member toward its normally supported position; and a further member movably mounted in connection with the tubing or the like and between which and said first 5 named movable member said last named means is disposed; said last named means comprising a coil compression spring; said frictional means comprising a bowed spring adapted to contact with the casing and co- 10 operating at spaced portions with said first and second named movable members; one of said movable members having an enlarged portion adapted to decrease the bowed formation of said spring upon the abrupt lowering 15 of the tubing or the like.

12. In combination with a string of tubing or other structure adapted to be lowered in a well casing; slips, means upon the string or other structure adapted to cooperate with the 20 slips to cause the same to wedge against the well casing; means co-acting with the slips and frictionally co-acting with the casing to permit the string or the like to be lowered with the slips in retracted position, and means 25 cooperating with said last named means for increasing the frictional action thereof upon a sudden lowering of the string or the like; said last named means including a movable member mounted in connection with said tubing and normally supported thereby; further means being provided urging said last 30 named member toward its normally supported position; and a further member movably mounted in connection with the tubing or the like and between which and said first named movable member said last named means is disposed; said last named means comprising a coil compression spring; said frictional means comprising a bowed spring 35 adapted to contact with the casing and co-operating at spaced portions with said first and second named movable members; one of said movable members having an enlarged portion adapted to decrease the bowed formation of said spring upon the abrupt lowering 40 of the tubing or the like; the other movable member being likewise reversable and having a second and more extensively enlarged portion.

14. In a device of the character disclosed, a string of tubing or the like adapted to be lowered in well casing, a slip or the like, means upon the tubing or the like to co-act with said slip or the like to cause wedge action of the slip between the casing and the tubing; friction means for cooperating with the casing and the slip and normally permitting the slip to occupy a retracted position, and means movably mounted in connection with the tubing for increasing the action of 50 said frictional means upon a sudden lowering of the tubing.

15. In a device of the character disclosed, a string of tubing or the like adapted to be lowered in well casing, a slip or the like, means upon the tubing or the like to co-act with said slip or the like to cause wedge action of the slip between the casing and the tubing; friction means for cooperating with the casing and the slip and normally permitting the slip to occupy a retracted position, and means movably mounted in connection with the tubing for increasing the action of 55 said frictional means upon a sudden lowering of the tubing; said frictional means comprising a normally bowed spring, and said movably mounted means cooperating with said spring to increase the frictional moment thereof.

16. In a device of the character disclosed, a string of tubing or the like adapted to be lowered in well casing, a slip or the like, means upon the tubing or the like to co-act with said slip or the like to cause wedge action of the slip between the casing and the tubing; friction means for cooperating with 60

the casing and the slip and normally permitting the slip to occupy a retracted position, and means movably mounted in connection with the tubing for increasing the action 5 of said frictional means upon the sudden lowering of the tubing; said frictional means comprising a normally bowed spring, and said movably mounted means cooperating with said spring to increase the frictional 10 moment thereof; and a slip actuator with which said spring co-acts and which slip actuator is connected with said slip.

17. In a device of the character disclosed, a string of tubing or the like adapted to be lowered in well casing, a slip or the like, means upon the tubing or the like to co-act with said slip or the like to cause wedge action of the slip between the casing and the tubing; friction means for cooperating with 20 the casing and the slip and normally permitting the slip to occupy a retracted position, and means movably mounted in connection with the tubing for increasing the action of said frictional means upon the sudden 25 lowering of the tubing; said frictional means comprising a normally bowed spring, and said movably mounted means cooperating with said spring to increase the frictional moment thereof; and a slip actuator with which 30 said spring co-acts and which slip actuator is connected with said slip; said means upon the tubing comprising a slidable member normally carried by the tubing and permitted to fall independently of the tubing upon abrupt 35 descent of the tubing.

18. In a device of the character disclosed, a string of tubing or the like adapted to be lowered in well casing, a slip or the like, means upon the tubing or the like to co-act with 40 said slip or the like to cause wedge action of the slip between the casing and the tubing; friction means for cooperating with the casing and the slip and normally permitting the slip to occupy a retracted position, and means movably mounted in connection 45 with the tubing for increasing the action of said frictional means upon the sudden lowering of the tubing; said frictional means comprising a normally bowed spring, and 50 said movably mounted means cooperating with said spring to increase the frictional moment thereof; and a slip actuator with which said spring co-acts and which slip actuator is connected with said slip; said means 55 upon the tubing comprising a slidable member normally carried by the tubing and permitted to fall independently of the tubing upon abrupt descent of the tubing; means for normally urging said last named and 60 means toward the position in which it is supported by the tubing.

19. In a device of the character disclosed, the combination with a string of tubing or the like adapted to be lowered in a well casing, a slip or the like adapted to cooperate 65

with the tubing or the like to be wedged between the tubing or the like and the casing; frictional means adapted to co-act with the casing and the slip to permit the gradual lowering of the tubing with the slip in retracted position, and means mounted in connection with the tubing for increasing the frictional moment of said last named means upon an abrupt drop of the tubing to cause 70 the slip to wedge between the tubing and the casing. 75

20. In a device of the character disclosed, the combination with a string of tubing or the like adapted to be lowered in a well casing, a slip or the like adapted to cooperate with the tubing or the like to be wedged between the tubing or the like and the casing; frictional means adapted to co-act with the casing and the slip to permit the gradual lowering of the tubing with the slip in retracted position, and means mounted in connection with the tubing for increasing the frictional coefficient of said last named means upon an abrupt drop of the tubing to cause 80 the slip to wedge between the tubing and the casing; said last named means being normally carried by the tubing and freed therefrom to fall independently of the tubing upon an abrupt drop of the tubing. 85

21. In a device of the character disclosed, the combination with a string of tubing or the like adapted to be lowered in a well casing, a slip or the like adapted to cooperate with the tubing or the like to be wedged between the tubing or the like and the casing; frictional means adapted to co-act with the casing and the slip to permit the gradual lowering of the tubing with the slip in retracted position, and means mounted in connection with the tubing for increasing the frictional coefficient of said last named means upon an abrupt drop of the tubing to cause 90 the slip to wedge between the tubing and the casing; said last named means being normally carried by the tubing and freed therefrom to fall independently of the tubing upon an abrupt drop of the tubing. 95

22. In a device of the character disclosed, the combination with a string of tubing or the like adapted to be lowered in a well casing, a slip or the like adapted to cooperate with the tubing or the like to be wedged between the tubing or the like and the casing; frictional means adapted to co-act with the casing and the slip to permit the gradual lowering of the tubing with the slip in retracted position, and means mounted in connection with the tubing for increasing the frictional moment of said last named means upon an abrupt drop of the tubing to cause the slip to wedge between the tubing and the 130

casing; said last named means being normally carried by the tubing and freed therefrom to fall independently of the tubing upon an abrupt drop of the tubing, and spring means acting in connection with said last named means; said slip normally resting upon said tubing independent of the action of said spring means; further means mounted movably in connection with the tubing and above said spring means; and said fric-

tional means comprising a normally bowed spring one portion of which rests upon said last named means; whereby upon an abrupt drop of the tubing said bowed spring is caused at its upper portion to be flexed toward a more bowed position. 15

In testimony whereof, I have signed my name to this specification.

NELSON K. SMITH.
